UNITED STATES PATENT OFFICE.

FRED F. PRIHODA, OF CHARLESTON, WEST VIRGINIA.

DISPENSING HOLDER.

1,425,416.

Specification of Letters Patent. Patented Aug. 8, 1922.

Application filed November 27, 1920. Serial No. 426,749.

To all whom it may concern:

Be it known that I, FRED F. PRIHODA, citizen of U. S. A., residing at Charleston, in the county of Kanawha and State of West Virginia, have invented new and useful Improvements in Dispensing Holders, of which the following is a specification.

This invention relates to cigarette cases or the like, and has for its chief characteristic the provision of a dispensing device of novel construction, said device being associated with the cigarette case to control the single delivery of cigarettes therefrom.

Another object of the invention resides in providing a stand for said case, the stand being constructed from a single length of wire and designed to provide a support for an ash tray which is arranged to one side of the cigarette case for the convenience of the users.

The nature and advantages of the invention will be better understood when the following detail description is read in connection with the accompanying drawings, the invention residing in the combination, construction and arrangement of parts as claimed.

In the drawings forming part of this application, like numerals of reference indicate the similar parts in the several views and wherein:

Figure 1 is a front elevation of my invention.

Figure 2 is a side elevation thereof.

Figure 3 is a vertical sectional view therethrough.

Figure 4 is a top plan view.

Figure 5 is a detail sectional view showing the relation of the dispensing device with the rear wall of the receptacle.

Referring to the drawings in detail 10 indicates a receptacle which may be constructed from any suitable material and also may vary in design without departing from the spirit of the invention, the invention being primarily intended to contain a plurality of cigarettes or articles of a similar configuration. The receptacle is provided with a removable cover 11, while the bottom 12 is inclined in a direction of the rear wall of the receptacle as shown. The bottom is provided with an opening 13 extended transversely across the bottom and in which opening operates the dispensing device to be presently described. This device is formed from a single piece of material and includes a

tray 14 adapted to project from the bottom of the receptacle, and a portion slidably fitted within the receptacle. This portion is joined with the tray 14 by means of the 60 curved portion 15 which defines a cigarette receiving channel, and also disposes the tray 14 obliquely to the portion above referred to which is slidably fitted within the receptacle 10. This latter mentioned portion includes 65 a straight wall 16 and a forwardly and downwardly inclined wall 17 which merges into the curved portion 15, while the lower edge of the straight wall 16 terminates to provide a flange 18. As stated this portion 70 is connected within the receptacle 10 to the straight wall 16 contacting the rear wall of the receptacle and holding it associated therewith by means of spaced pairs of lugs, 19 and 20, the lugs 19 of each pair being disposed above the lugs 20. These lugs are cut from the rear wall of the receptacle and bent inwardly in front of the vertical wall 16 of the device just described.

In normal position the parts of the cigarette receiving channel 15 are arranged beneath the bottom of the receptacle, and the inclined wall 17 of the device crosses the slot 13 to prohibit the escape of the cigarettes from the receptacle 10. When a 85 cigarette is desired the dispensing device is moved upwardly within the receptacle 10 by means of the tray 14 until the lowermost lugs 20 of each pair contacts the flange 18 thereby limiting the upward movement of 90 the device. In this position the channel 15 is arranged within the receptacle and is of a size to accommodate a single cigarette, so that when the tray 14 is released the device gravitates to normal position and brings out 95 with it the cigarette which is positioned within the channel 15, the cigarette rolling from the channel into the tray 14 as the device assumes its normal position. When the device is elevated the inclined wall 17 agitates the body of cigarettes in a manner to prevent jamming of the latter with resultant injury, and when the device gravitates to normal position the uppermost lugs 19 of each pair contacts the crossed end of the 100 device formed by the point of junction between the straight wall 16 and the inclined wall 17 thereby limiting the movement of the device in this direction.

A stand for the receptacle 10 is formed 110 from a single strand of wire bent to provide inverted substantially V-shaped por-

tions 22 which are connected by parallel members 23 the portions 22 embracing the opposed end walls of the receptacle as shown while the portions 23 rest upon the support. 5 One of the parallel portions 23 is extended beyond one side of the receptacle and terminates to provide a loop 24 to accommodate and support an ash tray 25 for the convenience of the user. Also projecting from 10 the front wall of the receptacle 10 is a holder 26 for a box of matches indicated at 29.

While it is believed that from the foregoing description the nature and advantages 15 of the invention will be readily apparent, I desire to have it understood that I do not limit myself to what is herein shown and described, and that such changes may be resorted to when desired, as fall within the 20 scope of what is claimed.

What I claim is:—

1. In combination, a receptacle having inclined bottom and an opening extending transversely thereof, a dispensing device including an inverted substantially V-shaped portion arranged within the receptacle for sliding movement, and a tray projecting forwardly from the bottom, one wall of the portion arranged within the receptacle normally closing the opening in the bottom 25 30

thereof, means for associating the device with the receptacle, and an article receiving channel formed on said device and adapted to receive an article when the device is moved within the receptacle, and delivering 35 the article upon the tray when moved in an opposite direction.

2. In combination, a receptacle having parallel side and front and rear walls, a detachable cover provided for its top, a bottom wall inclined downwardly toward the rear wall and provided with an elongated opening extending transversely thereof, a dispensing device including an inverted substantially V-shaped portion having a straight 40 45 vertical wall slidably secured to the rear wall of the casing and an inclined wall depending from the upper end of the straight wall and adapted to contact the inner edge of the opening in the inclined bottom wall 50 55 of the casing, a tray formed on the outer end of the device and arranged at an angle with respect to the V-shaped portion and a channel formed adjacent the end of the inclined depending wall and normally arranged below the opening as and for the purpose specified.

In testimony whereof I affix my signature.

FRED F. PRIHODA.
